(57) **CLAIM**

The ornamental design for an air conditioner with integrated thermal energy storage, as shown and described.

DESCRIPTION

FIG. 1 is an isometric view of an air conditioner with integrated thermal energy storage showing our new design.

FIG. 2 is a front elevation view thereof.

FIG. 3 is a top plan view thereof.

FIG. 4 is a left side elevation view thereof.

FIG. 5 is a right side elevation view thereof.

FIG. 6 is a rear elevation view thereof; and,

FIG. 7 is a bottom plan view thereof.
